Primary Examiner — Keith J Wilson(74) *Attorney, Agent, or Firm* — Sierra IP Law, PC; Mark D. Miller(57) **CLAIM**

The ornamental design for a showerhead nozzle as shown and described.

DESCRIPTION

FIG. 1 is a top perspective view of a showerhead nozzle showing my new design;

FIG. 2 is a left side elevational view thereof;

FIG. 3 is a front elevational view thereof;

FIG. 4 is a rear elevational view thereof;

FIG. 5 is a right side elevational view thereof;

FIG. 6 is a bottom plan view thereof; and,

FIG. 7 is a top plan view thereof.

The broken lines in the drawings indicate contour.

1 Claim, 4 Drawing Sheets
